Primary Examiner — Cynthia Ramirez*Assistant Examiner* — Xavier Marti-Santos(57) **CLAIM**

The ornamental design for a cosmetic facial mask, as shown and described.

DESCRIPTION

FIG. 1 is a perspective view of a cosmetic facial mask showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view in a second state;

FIG. 10 is another perspective view thereof; and,

FIG. 11 is an enlarged view of the encircled portion 11 of FIG. 1.

The broken lines in the drawings are for the purpose of illustrating portions of the cosmetic facial mask that form no part of the claimed design. The additional broken lines in FIG. 9 are to show environment and form no part of the claimed design. The dash-dot broken lines in FIGS. 1 and 11 are to show an area that has been enlarged, and form no part of the claimed design.

1 Claim, 11 Drawing Sheets(56)
